(57) **CLAIM**

The ornamental design for a portable basin assembly, as shown and described.

DESCRIPTION

FIG. 1 is an upper perspective view of a portable basin assembly according to a first embodiment;

FIG. 2 is a front view of a portable basin assembly according to a first embodiment;

FIG. 3 is a rear view of a portable basin assembly according to a first embodiment;

FIG. 4 is a first side view of a portable basin assembly according to a first embodiment;

FIG. 5 is a second side view of a portable basin assembly according to a first embodiment;

FIG. 6 is a top view of a portable basin assembly according to a first embodiment;

FIG. 7 is a bottom view of a portable basin assembly according to a first embodiment;

FIG. 8 is an upper perspective view of a portable basin assembly according to a second embodiment;

FIG. 9 is a front view of a portable basin assembly according to a second embodiment;

FIG. 10 is a rear view of a portable basin assembly according to a second embodiment;

FIG. 11 is a first side view of a portable basin assembly according to a second embodiment;

FIG. 12 is a second side view of a portable basin assembly according to a second embodiment;

FIG. 13 is a top view of a portable basin assembly according to a second embodiment; and,

FIG. 14 is a bottom view of a portable basin assembly according to a second embodiment.

In the drawings, the broken lines in the drawings illustrate environmental subject matter and form no part of the claimed design.
